ROCK DRILL

Elmer G. Gartin, Claremont, N. H., assignor to
Sullivan Machinery Company, a corporation
of Massachusetts

Application March 6, 1934, Serial No. 714,314

6 Claims. (Cl. 121—9)

This invention relates to rock drilling mechanisms, and more particularly relates to improvements in the feeding mechanism of a rock drill of the mounted drifter type.

5 An object of this invention is to provide an improved rock drill feeding mechanism. A further object is to provide an improved feeding mechanism for a rock drill of the mounted drifter type. Another object is to provide an improved pneumatic feeding mechanism having improved transmission connections between the feeding motor and the drill to be fed. Still another object is to provide an improved transmission means between the feeding motor and the drill to be fed and including flexible transmission elements and improved feeding connections actuated by said transmission elements, the motor having incorporated therein improved fluid sealing means, whereby leakage of the pressure fluid from the 20 motor is reduced to a minimum. Yet another object is to provide an improved speed multiplying mechanism between the feeding motor and the drill, whereby the drill is fed at a rate faster than the rate of movement of the power feeding element. These and other objects of the invention will, however, hereinafter more fully appear.

In the accompanying drawing there is shown, for purposes of illustration, one form which the invention may assume in practice.

30 In the drawing—

Fig. 1 is a central, longitudinally extending, vertical sectional view, with parts in elevation, showing the illustrative embodiment of the improved rock drilling mechanism.

35 Fig. 2 is a rear end elevational view, with parts shown in vertical section, of the improved drilling mechanism shown in Fig. 1.

Fig. 3 is a horizontal sectional view taken substantially on line 3—3 of Fig. 1.

40 Fig. 4 is a diagrammatic view showing two positions of the feed controlling valve.

In this illustrative construction there is shown a rock drilling mechanism of the mounted drifter type, although it will be evident that the improved feeding mechanism may be employed in drills of various other types. The rock drilling mechanism disclosed herein generally comprises a rock drill, generally designated 1, of a usual pressure fluid actuated hammer type, mounted for longitudinal movement on a guide shell 2 and having improved pneumatic feeding means, generally designated 3.

The improved feeding mechanism comprises aligned cylinders 4 and 5 having at their remote ends head members 6 and 7 and arranged be-

tween their adjacent ends a common head member or partition 8. This intermediate head or partition is herein formed integral with the feed cylinders, although it will be evident that the feed cylinders may be formed as separate elements to which the intermediate head is secured, and the heads 6 and 7 are suitably detachably secured to the cylinder. Formed on the bottom of the guide shell adjacent the intermediate head is a swivel plate 9 adapted to be clamped in the usual saddle mounting of a quarry bar or tripod support. Reciprocably mounted in the feed cylinders 4 and 5, respectively, are feed pistons 10 and 11, each having suitable cup packings 12 and rigidly secured together for movement in unison with respect to the cylinders by means of a common piston rod 13. These pistons are each secured to the piston rod against a collar 14 formed on the rod by a holding nut 15 threadedly secured to the rod, the piston being clamped by the nut against the collar. This piston rod extends through a central opening or bore 16 formed in the intermediate head or partition 8, and this opening is suitably packed, as by cup packings 17, for preventing leakage of fluid from the cylinders. 25 The opposite ends of the piston rod have formed therein sockets 18 each for receiving a suitable head 19 secured to a flexible transmission element 20, herein in the form of a wire rope or cable, the head 19 being secured within the socket 18 by a bushing 21 threaded within the end of the piston rod in the manner shown. The flexible transmission elements 20, 20 extend in opposite directions outwardly through the remote ends of the cylinders through openings 22 formed in the heads 6 and 7 and pass around guide sheaves 23 and 24, respectively, herein suitably journaled on shafts 24 carried by the heads 6 and 7. These flexible elements extend inwardly from the guide sheaves toward one another in a relation parallel with the feed cylinders, and are provided with heads 25 positioned within sockets 26 formed in a sliding block 27. The guide shell 2 is provided, as shown most clearly in Fig. 2, longitudinal guideways 28, 28, and the rock drill 1 is provided with longitudinal guides 29, 29 slidably arranged within these guideways. Also slidably guided within the guideways 28 is the sliding block 27, the latter being arranged within the guideways in the space between the guide bottom and the bottom of the rock drill, as shown in Fig. 2. Arranged in a chamber 30 formed in the sliding block 27 and journaled on a shaft 31 supported at its ends within the sides of the sliding block, is a spur pinion 32 meshing with a 35

relatively stationary rack 33 formed integral with the guide shell and a sliding rack 34 secured to the bottom of the rock drill. It will thus be seen that when the sliding block 27 is slid longitudinally in its guides with respect to the guide shell, the gear and rack mechanism forms a speed multiplying mechanism, whereby the rate of movement of the drill is somewhat greater than the rate of movement of the sliding block.

10 Now referring to the improved means for controlling the flow of pressure fluid to the feeding cylinders to effect reciprocation of the feed pistons, it will be noted that formed in the intermediate head 8 is a bore 36 in which is mounted a rotary valve 37, and this valve has a suitable control handle 38. The valve 37 is provided with a bore 39 to which pressure fluid is supplied through a flexible hose connection 40 connected by a T 41 to the usual fluid supply connection 42 of the rock drill, the connection 42 leading to any suitable source of pressure fluid supply. Connecting the valve receiving bore 36 with the interior of the feed cylinders 4 and 5 are fluid supply passages 44 and 45, while also communicable with 25 the valve receiving bore is a vent passage 46 leading to atmosphere. Formed externally on the valve 37 are circumferentially extending grooves 47 and 48, the former connected to the bore 39 in the valve through a passage 49. When the 30 control valve 37 is in the position *a* in Fig. 4, pressure fluid is supplied from the bore 39 of the valve through passage 49, groove 47 and the forward-feed passage 44 to the forward end of the rear feed cylinder 4 to act on the forward pressure area of the rear feed piston 10, thereby moving the piston rod 13 rearwardly, and through the flexible connections moving the sliding block 27 forwardly, causing the gear 32 to rotate; and as a result the rock drill 1 is fed forwardly at an increased rate along the guideways of the guide shell, the rear end of the front feed cylinder 5 at the rear side of the feed piston 11 at that time being connected to atmosphere through the passage 45, groove 48 and vent passage 46. When 40 the feed control valve is turned into the position *b* in Fig. 4, pressure fluid is supplied from the bore 39 in the valve through passage 49, groove 47 and the reverse-feed passage 45 to the rear end of the front feed cylinder 5, the pressure fluid acting on 45 the rear pressure area of the front feed piston 11, moving the latter and the piston rod forwardly, thereby drawing in the rear feed cable 20 and, through the speed multiplying connections, feeding the rock drill rearwardly along the guide shell, the forward end of the rear feed cylinder 4 at that time being connected to exhaust through 50 passage 44, groove 48 and vent passage 46. The remote ends of the feed cylinders 4 and 5 at the front and rear sides of the feed pistons 10 and 11, respectively, are vented to atmosphere through the openings 22 in the heads 6 and 7 through which the flexible transmission elements 20 extend. By arranging the feed pistons so that 55 pressure fluid acts only on the inner pressure areas thereof, and connecting the cables to the outer sides of the pistons, and by sealing the piston rod connection between the pistons, fluid leakage from the cylinder is reduced to a minimum while retaining the advantageous features of the flexible connections.

60 As a result of this invention, it will be noted that an improved pneumatic feeding mechanism for a rock drill of the mounted drifter type is provided, the improved feeding mechanism having associated therewith improved transmission

connections between the power feeding element and the drill to be fed. It will further be noted that an improved feeding mechanism is provided of the multi-cylinder and piston type having improved connections between the pistons and the drill to be fed and having incorporated therein improved fluid sealing means whereby cylinder leakage is reduced to a minimum. These and other uses and advantages of the improved rock drilling mechanism will be clearly apparent to those skilled in the art.

While there is in this application specifically described one form which the invention may assume in practice, it will be understood that this form is shown for purposes of illustration only 15 and that the invention may be modified and embodied in various other forms without departing from its spirit or the scope of the appended claims.

What I claim as new and desire to secure by 20 Letters Patent is:

1. In a rock drilling mechanism, the combination with a rock drill and guiding means therefor, of a feeding mechanism for feeding the rock drill in either of opposite directions along said 25 guiding means including aligned feed cylinders arranged alongside and parallel with said guiding means, feed pistons individual to and reciprocable in said feed cylinders respectively, means for connecting said pistons for movement in unison, a speed multiplying means common to both directions of movement of the drill and operatively connected to the drill for feeding the latter along said guiding means at a speed faster than the rate of movement of said feed pistons and including an element movable alongside said feed cylinders in a direction parallel with said guiding means, a flexible transmission connection between one feed piston and said element of said speed multiplying means, a separate flexible transmission connection between said other feed piston and said element of said speed multiplying means, and means for supplying pressure fluid selectively to said feed cylinders to act on one or the other of said feed pistons to effect drill 40 feed selectively in opposite directions along said guiding means.

2. In a rock drilling mechanism, in combination, a rock drill, and means for feeding the rock drill in either of opposite directions comprising 50 aligned feed cylinders, feed pistons reciprocable in said cylinders, a piston rod connecting said pistons together for movement in unison, brackets located at the remote ends of said cylinders, sheaves journaled on said brackets respectively, a speed multiplying means common to both feeding movements of the drill and operatively connected to the rock drill, movement of the rock drill in opposite directions being effected through said speed multiplying means, flexible transmission elements between the opposite ends of the piston rod and said speed multiplying means and guided by said sheaves, and means for supplying pressure fluid selectively to the adjacent ends of said feed cylinders to act on one or the other 60 of said feed pistons.

3. In a rock drilling mechanism, in combination, a rock drill, and feeding mechanism for the rock drill comprising aligned feed cylinders, feed pistons reciprocable in said cylinders respectively, 70 a common piston rod connecting said feed pistons together for movement in unison, a sliding block, flexible connections between the opposite ends of said piston rod and said sliding block, a rack on the rock drill, a rack secured against 75

movement longitudinally with respect to said feed cylinders and arranged alongside of the latter, a gear carried by said sliding block and meshing with said racks, and means for supplying pressure fluid selectively to the adjacent ends of said feed cylinders to act on one or the other of said pistons to effect drill feed in either of opposite directions.

5. In a rock drilling mechanism, in combination, a rock drill, guiding means providing a longitudinal guideway on which the drill is guided for movement longitudinally of the guiding means, and means for feeding the rock drill along said guideway comprising a pneumatic 10
10 feeding motor mounted on said guiding means and arranged in parallel side by side relation with said guideway, said feeding motor comprising a feed cylinder member, a feed piston reciprocable therein, a sliding block, a cable connecting 15
15 said feed piston to said sliding block, a gear carried by said sliding block, a relatively stationary rack with which said gear meshes, said rack extending longitudinally of said feeding motor in parallelism with said guideway and 20
20 between the ends thereof, and a rack secured to the rock drill and with which said gear meshes. 25
25 5. In a rock drilling mechanism, a guideway, a pair of alined cylinders having an intermediate common cylinder head and extending parallel to 30
30 said guideway and arranged with said head between and spaced substantially from the opposite ends of said guideway, pistons in said cylinders having a piston rod connecting them and passing through said common head, a drilling 35
35 motor movable on said guideway, means including

speed multiplying mechanism for operatively connecting the relatively remote ends of the pistons to feed said drilling motor, said speed multiplying means including cooperating speed multiplying elements and a block carrying an element of said speed multiplying means and moving between the relatively remote ends of the cylinders and connected at its opposite ends respectively to different pistons, and means for supplying pressure fluid selectively to said feed cylinders to act on one or the other of said feed pistons to effect drill feed in either of opposite directions.

6. In a rock drilling mechanism, in combination, a rock drill, and means for feeding the drill 15
15 including a pneumatic feeding motor comprising alined cylinders each containing a reciprocable piston, and a common piston rod for connecting said pistons for movement in unison, means for selectively supplying pressure fluid to the adjacent ends of said cylinders to act on one piston or the other to effect movement of the piston rod in one direction or the other, a speed multiplying means operatively connected to the drill and including a movable element, and connections between the opposite ends of the piston rod and said element of said speed multiplying means for moving said element in opposite directions at the same speed as the rate of movement of said piston rod, said speed multiplying means 20
20 comprising elements cooperating with said movable element for multiplying the speed between said movable element and the rock drill whereby the drill is fed at a multiplied rate of speed.
